UNITED STATES PATENT OFFICE.

GARTH G. GILPIN, OF RIVERSIDE, ILLINOIS, ASSIGNOR TO P. H. MURPHY COMPANY, OF NEW KENSINGTON, PENNSYLVANIA, A CORPORATION OF PENNSYLVANIA.

CAR ROOF.

Application filed April 4, 1921. Serial No. 458,502.

To all whom it may concern:

Be it known that I, GARTH G. GILPIN, a citizen of the United States, residing at Riverside, in the county of Cook and State 5 of Illinois, have invented new and useful Improvements in Car Roofs, of which the following is a specification.

This invention relates to improvements in car roofs and more particularly to roofs 10 for freight cars of the type known as all metal roofs.

It is an object of this invention to construct a roof of this type in which the roof sheets extend from side to side of the car, are 15 supported on carlines arranged exteriorly of the roof sheets and to which the roof sheets are secured in such a manner as to form water-tight joints. It is a further object of this invention to simplify the construction 20 and assembly of parts by forming the roof sheets from rectangular blanks of the same dimensions and forming the carlines by pressing from rectangular blanks of metal.

The advantages of this construction are 25 that extremely strong roofs of light weight metal may be applied to freight cars without the use of purlins or ridge poles and also provide the maximum amount of head-room as the carlines supporting the roof sheets 30 on the exterior of the roof. Another advantage is that the rivets employed for securing the roof sheets to the carlines lie in a horizontal plane and thereby should the rivets become loose in service the rivet holes 35 will not afford ready access for rain or water to drain into the body of the car. An additional advantage is that the peculiar formation of the carlines at the eaves affords a means for ventilation tending to equalize 40 the temperature on both sides of the roof sheets which will reduce the tendency of the metal to sweat.

While the preferred form of this invention is illustrated upon the accompanying 45 sheets of drawings yet minor detail changes may be made without departing from the scope thereof.

In the drawings:

Figure 1 is a top plan view of a portion 50 of a freight car roof embodying this invention.

Figure 2 is a vertical sectional view taken on the line 2-2 of Figure 1.

Figure 3 is a view in side elevation of 55 Figure 1 with parts broken away.

Figure 4 is a view in section taken on the line 4-4 of Figure 2.

Figure 5 is a view similar to Figure 4, illustrating a modified means of attaching the running board saddles to the carlines.

Figure 6 is a view similar to Figure 4, illustrating a modified form of running board saddle.

Figure 7 is a view in section taken on the line 7-7 of Figure 1.

In carrying out this invention the roof sheets 1, extend from side to side of the car body and are bent downward at the eaves over the side plates. In this form the side plates are composed of angle irons 2 with the upper members arranged in the same horizontal plane. Wooden filler blocks 3 are preferably interposed between the side plates and underside of the roof sheets, the upper and outer surfaces of which are inclined and curved so that the roof sheets extending thereover and therebeyond may rest thereon and then be bent gradually downward over the exterior of the side plates. The eaves edges and roof sheets are secured to angles 4, which in turn are riveted to the side plates, as shown. The side edges of each roof sheet are provided with continuous upstanding flanges 5, of constant height.

Inverted U-shaped carlines 6 having outstanding flanges 7 on their side walls are placed over the spaced apart flanged meeting edges of the roof sheets with the outstanding flanges of the carlines resting upon the body of the roof sheets and the roof sheet flanges are secured on the inside of the carline side wall by a plurality of horizontal disposed rivets. The carlines at the ridge are of greater height than the roof sheet flanges and constantly decrease in height from ridge to eaves until the tops of the carlines contact with the tops of the roof flanges over the side plates and the eaves ends of the carlines are extended beyond and bent downward over the side plates with the outstanding flanges following the contour of the body of the roof sheets, and the lower ends of these flanges are riveted to the angle irons securing the roof sheets of the side plates.

The inverted U-shaped carline being of greatest height at the ridge is strongest where the greatest strength is needed. The outstanding flanges of the carlines increase

in width from ridge to eaves proportionately to the decrease in height of the carline and the carline flanges being of greatest width at the eaves give additional strength to the carlines to resist the torsional strain of weaving. The carlines not only support the roof sheets but act as seam caps as well, with each side of the carline forming a watertight joint with the adjacent roof sheet.

10 This form of carline is readily pressed from a rectangular sheet of metal.

The running boards 8 are preferably supported on saddles consisting of oblong blocks of wood 9 resting upon the body of the roof sheet and against the side wall of the adjacent carline. It is preferable to secure the wooden saddle 9 by a bolt to the carline side walls, as shown in Figures 1, 4 and 5. As illustrated in Figures 1 and 4 the side wall of the carline over the ridge is provided with an offset 10 below the top of the adjacent roof sheet flange through which the bolt 11 is passed at an angle to the roof sheet as shown. If desired an offset 10^a may be struck from the side wall of the carline near the top thereof so that the lower part of the off-set wall will be parallel to the side wall and the bolt securing the saddle block thereto will lie in a horizontal plane, as shown in Figure 5. A metallic running board saddle is shown in Figure 6 which comprises a rectangular plate 12 having one edge secured to a side wall of the carline by the same rivets that secure the carline and roof sheet flange which plate is bent over and rests upon the top of the carline, is riveted thereto, and then extends therebeyond terminating in an upward offset 13 which supports the running boards 40 above the heads of the latter rivets.

What I claim is:

1. In an all metal car roof, roof sheets having their eaves ends secured to the car side plates and having spaced apart adjacent edges provided with continuous upstanding flanges, inverted U-shaped combined carlines and seam caps thereover having outstanding flanges on their side walls resting upon the body of the roof sheets, and a plurality of horizontally disposed rivets securing the roof sheet flanges to the side walls of the carlines.

2. In an all metal car roof, roof sheets having their eaves ends secured to the outer side of the car side plates and having spaced apart adjacent edges provided with continuous upstanding flanges, inverted U-shaped combined carlines and seam caps thereover having outstanding flanges on their side walls resting upon the body of the roof sheets, means securing the roof sheet flanges to the side walls of the carlines, and means securing the eaves ends of the carlines to the outer side of the car side plates.

3. In an all metal car roof, roof sheets having their eaves ends secured to the car side plates and having spaced apart adjacent edges provided with continuous upstanding flanges, inverted U-shaped combined carlines and seam caps thereover having outstanding flanges on their side walls resting upon the body of the roof sheets, said carlines and seam caps being of greater height than the roof sheet flanges at the ridge and decreasing in height towards the eaves, and a plurality of horizontally disposed rivets securing the roof sheet flanges to the side walls of the carlines.

4. In an all metal car roof, roof sheets having their eaves ends secured to the car side plates and having spaced apart flanged edges, inverted U-shaped combined carlines and seam caps thereover having outstanding flanges on their side walls increasing in width from ridge to eaves and resting upon the body of the roof sheets, means securing the roof sheet flanges to the side walls of the carlines, and means securing the flanges of the carlines to the car side plates.

5. In an all metal car roof, roof sheets having their eaves ends secured to the car side plates and having spaced apart adjacent edges provided with continuous upstanding flanges, inverted U-shaped combined carlines and seam caps thereover having outstanding flanges on their side walls resting upon the body of the roof sheets, said carlines and seam caps being of greater height at the ridge than the roof sheet flanges and decreasing in height towards the eaves ends and said outstanding flanges increasing proportionately in width from the ridge to the eaves, and means securing the roof sheet flanges to the side walls of the carlines.

6. In an all metal car roof, roof sheets extending from side to side having their eaves ends secured to the car side plates and having spaced apart flanged edges, inverted U-shaped combined carlines and seam caps thereover having outstanding flanges on their side walls resting upon the body of the roof sheets, said roof sheets, carlines and seam caps resting upon the side plates, extending thereover and bent down therebeyond, means securing the roof sheet flanges to the side walls of the carlines, and means securing carlines to the car side plates.

7. In an all metal car roof, roof sheets extending from side to side and having spaced apart flanged edges, inverted U-shaped combined carlines and seam caps thereover having outstanding flanges on their side walls resting upon the body of the roof sheets, a plurality of horizontally disposed rivets securing the roof sheet flanges to the side walls of the carlines, said roof sheets, carlines and seam caps resting upon the car side plates extending thereover and bent down therebeyond, and means on the exterior of the side

plates for securing the roof sheets, carlines and seam caps thereto.

8. In an all metal car roof, roof sheets extending from side to side and having spaced apart edges provided with continuous upstanding flanges of uniform height, inverted U-shaped combined carlines and seam caps thereover of greater height at the ridge than the sheet flanges and decreasing in height 10 towards the eaves having outstanding flanges on their side walls increasing in width from ridge to eaves resting upon the body of the roof sheets, a plurality of horizontally disposed rivets securing the roof sheet flanges 15 to the side walls of the carlines, said roof sheets and carlines resting upon the car side plates, extending thereover and bent down therebeyond, and means including an angle for securing the eaves ends to the roof sheets 20 and carline flanges to the exterior of the car side plates.

9. In an all metal car roof, roof sheets ex-

tending from side to side and having spaced apart edges provided with continuous upstanding flanges of uniform height, inverted 25 U-shaped combined carlines and seam caps thereover of greater height at the ridge than the sheet flanges and decreasing in height towards the eaves having outstanding flanges on their side walls increasing in width from 30 ridge to eaves resting upon the body of the roof sheets, a plurality of horizontally disposed rivets securing the roof sheet flanges to the side walls of the carlines, said roof sheets and carlines resting upon the car side 35 plates, extending thereover and bent down therebeyond, means including an angle for securing the eaves ends of the roof sheets and carline flanges to the exterior of the car side plates, and filler blocks interposed between 40 the tops of the car side plates and the roof sheets.

GARTH G. GILPIN.
